[57] CLAIM

The ornamental design for a heart-shaped cap, as shown and described.

DESCRIPTION

FIG. 1 is a perspective view of my design;
FIG. 2 is a front view thereof;
FIG. 3 is a back view thereof;
FIG. 4 is a top plan view thereof;
FIG. 5 is a bottom plan view thereof;
FIG. 6 is a right side elevational view thereof; and,
FIG. 7 is a left side elevational view thereof.
The broken line showing of internal elements in the interior of the heart-shaped cap is for illustrative purposes only and forms no part of the claimed design.
